E. W. RUTHERFORD.
VULCANIZING APPARATUS.
APPLICATION FILED FEB. 6, 1915.

1,209,764.

Patented Dec. 26, 1916.

UNITED STATES PATENT OFFICE.

EUGENE W. RUTHERFORD, OF NAUGATUCK, CONNECTICUT, ASSIGNOR TO BOSTON
RUBBER SHOE COMPANY, A CORPORATION OF MASSACHUSETTS.

VULCANIZING APPARATUS.

1,209,764.

Specification of Letters Patent. Patented Dec. 26, 1916.

Application filed February 6, 1915. Serial No. 6,418.

To all whom it may concern:

Be it known that I, EUGENE W. RUTHERFORD, a citizen of the United States, and a resident of Naugatuck, county of New Haven, and State of Connecticut, have invented certain new and useful Improvements in Vulcanizing Apparatus, of which the following is a full, clear, and exact description:

This invention relates to apparatus used in controlling the internal and external pressures exerted upon articles embodying rubber, rubberlike, or similar materials during the process of vulcanization.

An object of the present invention is to provide means whereby a controllable differential of pressure may be independently exerted upon different units of the apparatus at any time during cure, whereby a saving in cost of production as well as an increased output for a single vulcanizer will be promoted.

Ordinarily, in vulcanizing under the controllable differential of pressure process, the articles, such as for instance, boots or shoes, are built in the usual manner upon hollow perforated boot trees. These boot trees are mounted upon a car the frame of which is formed of tubing, there being branch pipes of this tubing connected with the interior of the hollow boot trees. The car carrying the boot trees with the articles to be vulcanized thereon is run into a vulcanizer wherein the outside of the articles is subjected to heat and controllable high pressure. The car tubing is connected to a controllable low pressure or even vacuum pipe, whereby the inside of the articles is subjected to a lesser pressure than the outside, this differential of pressure serving to exhaust enclosed air, gases, fluids, and the like from the articles.

The present invention provides apparatus embodying a plurality of cars or units of the above described type in combination with a common exhaust or low pressure pipe from which branches lead to respective cars or units, these branches being controlled by corresponding valves, each of which may be opened in turn independently of the others to exhaust the articles on the corresponding car. By this selective method of exhausting the articles upon but one car at a time, a single low pressure or vacuum device of only sufficient capacity to exhaust the articles upon one unit may be employed,

thus producing a saving in cost over operating a large device of sufficient capacity to exhaust all the cars or units simultaneously.

An apparatus suitable for carrying out the invention is illustrated in the accompanying drawing, in which:

Figure 1 is a plan view of the apparatus with parts in section; Fig. 2 is a cross section on the line 2—2, Fig. 1.

Referring now to the drawing, 10 designates a car which is mounted upon wheels 11, which facilitates the car being run upon a track 12, into a vulcanizer 13, of the usual and well known type. The frame of the car is formed of tubing from which branch pipes 14 rise, these pipes being suitably connected to and serving to support the hollow boot trees upon which the boots 15 are supported. In the present embodiment heat and pressure are supplied to the articles by means of a perforated steam pipe 16.

In carrying out the invention I provide a main low pressure or exhaust pipe 17 which is operatively connected with a suitable pump 18 or similar device, and is provided at intervals with branch pipes 19, which enter the vulcanizer and are controlled by corresponding valves 20, disposed outside of the vulcanizer. The branch pipes 19 are detachably connected to corresponding units 21 or cars 10, and for this purpose the tubing of each car carries a pipe 21 adapted to be coupled to a respective branch pipe 19 of the low pressure or exhaust pipe, by means of a coupling 22 of any preferred type.

In operation, after the cure of the articles has been started in the usual manner, each unit of the series of cars is put into communication with the low pressure or exhaust device independently of the others by opening its corresponding valve 20, such communication being cut off after an interval of from three to fifteen minutes, more or less, and another unit opened to the action of the low pressure or exhaust, this operation being continued until all of the units have been put in turn in communication with the low pressure or exhaust.

It is not necessary that the articles be subjected to the low pressure or exhaust during the period of vulcanization, since this operation may be performed prior to the commencement of the vulcanizing operation. I do not wish to limit myself to any particular sequence of putting the various units or cars

in communication with the exhaust, neither do I limit myself to any particular length of time during which the articles of any particular unit shall be subjected to the action 5 of the vacuum or exhaust, neither do I limit myself to any particular stage of the vulcanizing operation at which the articles shall be subjected to the action of the exhaust.

What I claim is:

- 10 A vulcanizing apparatus comprising a vulcanizer, a plurality of independent pipes entering the vulcanizer, respective valves for controlling said pipes, a common pipe connected with said valve controlled pipes, an

exhaust device connected with said common 15 pipe, a plurality of units formed of tubing, means for supporting vulcanizable plastic articles upon said units, and establishing communication between said articles and said tubing, and respective couplings between said valve controlled pipes and said tubing units. 20

Signed at Naugatuck, Conn., this 3rd day of February, 1915.

EUGENE W. RUTHERFORD.
